UNITED STATES PATENT OFFICE

PERCY O. HAWKINS, OF HAMMOND, INDIANA, ASSIGNOR OF ONE-HALF TO GEORGE A. RUST, OF WORTH, ILLINOIS

EXCAVATING MACHINE

Application filed July 25, 1931. Serial No. 553,035.

My invention relates to an excavating device or shovel and has for one purpose the provision of an excavating shovel of an improved type. One object is the provision of means for moving said shovel substantially directly forwardly a considerable distance prior to its upward lift. Another object is the provision of improved means for supporting such a shovel. Another object is the provision of an improved crowding means for such a shovel. Another object is the provision of an improved cable connection for actuating such shovel. Other objects will appear from time to time in the course of the specification and claims.

I illustrate my invention more or less diagrammatically in the accompanying drawings, wherein—

Figure 1 is a side elevation with the shovel in excavating or crowding position;

Figure 2 is a similar view with the shovel lifted;

Figure 3 is a plan view of the structure shown in Figure 1; and

Figure 4 is a side elevation illustrating a rearrangement of the parts for drawing the shovel toward the base structure.

Like parts are indicated by like symbols throughout the specification and drawings.

Referring to the drawings, A generally indicates any suitable base or body which may be supported for example upon the endless track or crawler structure A¹ including the wheels or pulley A². An suitable means may be employed for actuating such endless track or supporting structure and since the details do not of themselves form part of the present invention, they are not herein shown.

B, B¹ generally indicate portions of an A-frame, the members B and B¹ being secured together as at B². Pivoted as at B³ is the boom B⁴. Also pivoted at B³ is a brace B⁵ to the upper end of which is pivoted, as at B⁶, the arm or link B⁷. The link has at its opposite ends the sheaves B⁸ and B⁹ and the boom B⁴ is provided with the terminal sheave B¹⁰ and an intermediate sheave B¹¹.

C indicates the bucket stick which may be pivoted to the arm B⁷ for example concentrically with the sheave B⁹. C¹ indicates

any suitable bucket at the lower end thereof with a bottom or door C² pivoted thereto as at C³. C⁴ is a sheave mounted for example in the yoke or stirrup C⁵, also pivoted to the bucket C¹. C⁶ indicates any suitable latch for the bucket closure C² which may for example normally be kept in locking position by the spring C⁷. C⁸ indicates a bucket opening line or cable passing around the sheaves C⁹ C¹⁰ and C¹¹ and terminating at the control lever C¹². It will be noted that the sheave C⁹ is mounted concentric with the connection between the bucket stick C and the arm B⁷. The sheave C¹⁰ is mounted concentric with the connection between the support B⁵ and the arm B⁷. The sheave C¹¹ is concentric with the connection between the support B⁵ and the base of the A-frame member B. Thus the length of the line C⁸ is not substantially varied by movement of the bucket and its supporting parts. A counter-clockwise movement of the lever C¹² will serve to open the bucket by drawing the latch C⁶ against the spring C⁷.

I provide a plurality of concentrically mounted drums D D¹ which may be actuated by any suitable hoisting mechanism the details of which are not herein shown. I provide, however, separate control levers D² D³ for the actuation of the two drums. Dead-ended on the drum D¹ is the pull-back cable D⁴ which passes about the sheave B⁸ and is dead ended at the top of the A-frame at the junction of the members B and B¹.

E indicates the hoist and crowd cable, one end of which may be dead ended on the drum D¹. The cable then passes about the intermediate sheave B¹¹ on the boom, then about the sheave B⁹ at the outer end of the arm B⁷, at which point it effects its primary crowding function. It then passes about the terminal sheave B¹⁰ at the outer end of the boom and about the bucket sheave C⁴ and is dead ended as at E¹ adjacent the outer end of the boom. E² indicates the boom cable which is dead ended upon a separate smaller drum E³ and passes about a sheave E¹⁰ at the top of the A-frame, thence about a small sheave E⁴ at the top of the boom, thence about the sheaves E⁵ E⁶, thence back to another

small sheave E^7 at the end of the boom and thence back to be dead ended as at E^8 at the top of the A-frame.

Referring to Figure 4 I illustrate a variant form of my device in which with a very slight change in the structure, I convert my device into a pull shovel without the use of additional parts or material. For example the bucket C^1 is simply reversed on the bucket stick C or rather the bucket and stick are both reversed. This reversal may be obtained for example by pivoting the stick C to the arm B^7 by means of any suitable removable pivot pin G . When the pin is removed the stick is reversed and the bucket is then in the position in which it is shown in Figure 4. This necessitates a rearrangement of the cable and changes the function of the arm B^7 which may be bolted in the position in which it is shown in Figure 4 as by employment of the bolt or bolts G^1 passing through the lugs $G^2 G^3$ on the support B^5 and the arm B^7 respectively. In other words the arm B^7 then becomes a part of or a short extension of the support B^5 , the two operating in unison as a single member. The sheaves $B^8 B^9$ may be left in position but are not employed.

I then employ a pull cable H dead ended on the drum D and dead ended as at H^1 on the bucket C^1 . H^2 indicates a cable which may be called a hoist cable which extends from the drum D^1 about the sheaves B^{11} and B^{10} to the bucket C^1 to which it is dead ended as at H^3 .

It will be realized that whereas I have described and shown a practical and operative device, nevertheless many changes may be made in size, shape, number and disposition of parts without departing from the spirit of my invention. I wish my drawings, therefore, to be taken as in a broad sense illustrative and diagrammatic rather than as limiting me specifically to the details of the present showing. For example while I have illustrated a practical arrangement of cables it will be understood that under some circumstances the cable arrangements may be more or less varied.

It will also be understood that where in my claims I specify a support pivoted to the base, I wish this limitation to be interpreted sufficiently broadly to cover the pivotal supporting of the support B^5 on the base, either by being directly pivoted to the base, or by being pivoted to some intermediate member, such as the boom B^4 .

The use and operation of my invention are as follows:

Considering first the parts in the arrangement in which they are shown in Figures 1, 2 and 3, the cable E^2 serves simply to raise and lower the boom B^4 in the usual manner. The bucket stick C is pivoted at one end of the arm B^7 which in turn is pivoted to the upper end of the support B^5 , such support

being pivoted at the base of the boom and A-frame as at B^3 . Note that the boom B^4 and the support B^5 are concentrically pivoted. The result is a very flexible support for bucket stick and bucket. In the cables as shown in Figures 1, 2 and 3 the cable E actuates the bucket. It will be noted that the sheave B^9 is at the end of a rear bend of the cable between the sheaves B^{11} and B^{10} . Therefore, pulling on the cable E tends to move the sheave B^9 forwardly along a generally horizontal line for a considerable distance. The result is a very efficient crowding action exerted at the sheave B^9 , which moves the upper end of the stick C directly forward. This crowding action is substantially entirely controlled by paying off the line D^4 . The extent to which this line is paid off limits the forward crowding movement as of course unless D^4 is paid off the sheave B^3 serves to hold the arm B^7 in position. The outer bend of the cable E , which passes about the bucket sheave C^4 effects the lifting action on the bucket and when the arm B^7 is held against movement by failure to pay out the cable D^4 then the bucket stick C rotates about its pivot and the bucket describes an arc about the sheave B^9 as a center. As the stick C is pivoted at its upper end, the radius of the arm is equal to the length of the stick C and the bucket C^1 . This is in contrast to the old practice in which the stick is pivoted intermediate its ends and I thus get the advantage of having the entire length of stick and bucket for radius. This, in comparison to prior practice, is a gain of over one-third in the length of the radius, in addition to the increased crowding effect of permitting the pivot point itself to move forwardly until it strikes the boom. In the present device the bucket may be carried on grade forwardly a distance of about ten feet or somewhat more, whereas in the known types of bucket now on the market the forward movement on grade of the bucket is at a maximum of about three feet and is generally less than three feet. In other words it takes a big shovel of the present type to cut three feet on grade. The device herein shown more than triples the present general limit of forward bucket movement on grade. The operator, in order to control this grade movement, simply controls the payoff of the cable D^4 , which can continue until the rocker arm actually abuts against the boom in the position in which it is shown for example in Figure 2. Then continued drawing in on the cable E rotates the stick C about its pivot until it reaches its fully extended position, as shown in Figure 2. Then the operator actuates the lever C^{12} to release the head C^2 and permit the load to fall at any desired time. It will be also understood that when the device is in fully extended position, as in Figure 2, the operator may hold the gate locked until it is drawn

back on the cable D^4 approximately the length of the stick C . Thus the bucket may be dumped in any position between the fully extended position shown in Figure 2 and the fully withdrawn position above described.

- 5 An advantageous feature of my device rests in the fact that when the bucket C^1 is in withdrawn position at the beginning of its excavating travel it rests nearly flat on the ground, in contrast to the prior art buckets 10 in which when the bucket is drawn back as far as possible, the bucket stick is at an acute angle to the horizontal in the old type and the bucket teeth rest on and dig into the ground at approximately a 45 degree angle. As a 15 result the initial movement plows up the ground and the teeth produce a very rough finish. In my device, on the contrary, the bucket rests so flat that the teeth do not dig into the ground and a relatively smooth surface 20 is produced from the very starting point of the bucket. Referring to Figure 1, if the cable D^4 is drawn in a little farther the support B^5 is vertical and when in such position before the excavation begins, by paying off 25 the cable D^4 the bucket may be dropped substantially vertically to the ground or surface. Prior to the excavating stroke it may be supported somewhat above the ground at any 30 desired point. When by paying off the cable D^4 it has been dropped to the ground, then the conjoint employment of the cables D^4 and E , paying off and drawing in to suit the 35 situation, effects the excavating function. In effect the grade is controlled by paying off the cable D^4 while cable E is in operation or is being drawn in. When the cable E is drawn in its moves the bucket out, and when, at the same time, the cable D^4 is paid out, 40 it controls the grade by permitting forward movement of the upper end of the stick. By permitting the upper end of the stick to float forward with the bucket I get a horizontal planing action which is characteristic of the use of my structure.
- 45 A further advantageous use of my device is in excavating basements or the like where a vertical movement of the bucket is desirable at the end of a horizontal movement. Thus, I can get a vertical bank. I obtain this 50 effect by maintaining cable E taut, without causing the bucket to move forwardly any farther, and then draw in on the cable D^4 . This rocks the entire bucket supporting structure and while it is being rocked the operator 55 may pay off slightly on cable E . By this means a vertical bank may be dug and the bucket may be lifted over such a bank and dumped on the other side. This is useful 60 for example in foundation excavation.

In referring to the form of Figure 4 it is possible by a very slight change, as above described, to convert my device into a hoe or pull-shovel. By merely reversing the 65 stick C and the shovel C^1 and by lowering the

boom it is possible to dig a ditch approximately 8 feet deep, for by lowering the boom B^4 it is possible to excavate far below the level of the caterpillar or endless track A^1 . In this case the cable H serves as a draw cable for pulling in on the bucket and for giving it its actual digging impulse. The cable H^2 is a bucket lifting cable and the cables H and H^2 between them serve positively to position the bucket C^1 . The pivotal intersection between the stick C and the unitary member B^5 B^7 floats free. The cable C^8 may be omitted, since the bucket may dump out of its front or mouth rather than through its gate or back.

I claim:

1. In an excavating device, a base, a boom, a support pivoted to the base, a rocker arm pivoted intermediate its ends to said support, a bucket stick pivoted to said arm, sheaves mounted at the opposite ends of said rocker arm, a plurality of hoisting drums, a pull back cable associated with one of said drums and passing about a sheave on one end of said arm and a crowding and bucket hoisting cable associated with another said drum and passing about a sheave at the opposite end of said rocker arm. 70
2. In an excavating device, a base, a boom, a support pivoted to the base, a rocker arm pivoted intermediate its ends to said support, a bucket stick pivoted to said arm, sheaves mounted at the opposite ends of said rocker arm, a plurality of hoisting drums, a pull back cable associated with one of said drums and passing about a sheave on the inner end of said arm and a crowding and bucket hoisting cable associated with another said drum and passing about a sheave at the outer end of said rocker arm. 75
3. In an excavating device, a base, a boom, a support pivoted to the base, a rocker arm pivoted intermediate its ends to said support, a bucket stick pivoted to one end of said rocker arm and cable means for actuating said bucket stick. 80
4. In an excavating device, a base, a boom, a support pivoted to the base, a rocker arm pivoted intermediate its ends to said support, a bucket stick pivoted to one end of said rocker arm and cable means for actuating said bucket stick, including a pull back cable associated with one end of the rocker arm and a crowding cable associated with another end of the rocker arm and with the bucket stick. 85
5. In an excavating device, a base, a boom, a support pivoted to the base, a rocker arm pivoted intermediate its ends to said support, a bucket stick pivoted to said arm, sheaves mounted at the opposite ends of said rocker arm, a plurality of hoisting drums, a pull back cable associated with one of said drums and passing about a sheave on one end of said arm and a crowding and bucket hoisting cable associated with another said drum and passing about a sheave at the opposite end of said rocker arm. 90

cable associated with another said drum and passing first about a sheave positioned intermediate the ends of the boom, then about a sheave at one end of the rocker arm, then about a terminal boom sheave, then about a bucket sheave, said cable being dead ended upon the boom.

6. In an excavating device, a base, a boom, a support pivoted to the base, a rocker arm pivoted intermediate its ends to said support, 10 a bucket stick pivoted to one end of said rocker arm and cable means for actuating said bucket stick, and a bucket at the lower end of said bucket stick, said bucket stick being reversibly mounted upon said rocker arm.

7. In an excavating device, a base, a boom mounted on the base, a support in pivotal relationship with the base, a rocker arm pivoted, intermediate its ends, adjacent the top 20 of said support, a bucket stick pivoted to one end of the rocker arm and cable means for actuating said bucket stick, the rocker arm being normally freely rotatable in relation to the support to which it is pivoted, means for holding the rocker arm against rotation in relation to the support, the bucket stick being reversible in relation to the rocker arm.

25 30 Signed at Chicago, county of Cook and State of Illinois, this 16th day of July, 1931.
PERCY O. HAWKINS.
